SHANK PIECE

Louis Beckerman, Auburn, Maine, assignor to M. Beckerman & Sons, Inc., Auburn, Maine, a corporation of Maine

Application June 14, 1951, Serial No. 231,567

1 Claim. (Cl. 36—76)

1

This invention relates to shoes; more particularly to sling type shoes, methods of producing the same and a tuck or shank piece construction therefor.

My invention concerns itself with the problem of making women's shoes, and particularly the sling type shoe. Known to me in the latter type of construction is the production of the shoe to include a tuck or shank reinforcing supporting assembly which is positioned between the outsole and the liner or insole, comprising a stiffener as a carrier, to which a metal shank reinforcement is applied, and which is edged by an edging, binding strip visible in the open heel as a layer between the insole or liner and the outsole. The production of such a tuck or shank piece and its assembly in the shoe involves the costly operation of edging, as well as to lead to a cumbersome or awkward and heavy appearance in exposing the edging between the insole or liner and the outsole.

The finished edging likewise places a limitation on the perfection of alignment with the outsole and the matching of the color or the edging or binding with the finish of the heel and the upper. Likewise, the inflexibility of the tuck or shank piece at peripheral edges limits or makes unnecessarily burdensome the shaping of the assembly of outsole, tuck or shank reinforcement, to secure the desired rigidity in the shank, while obtaining maximum uniformity and accuracy.

Accordingly, it is an object of my invention to provide a woman's shoe, particularly a flexible woman's shoe and still more particularly, an open heel or sling type of shoe which is pleasing in appearance, simplifies manufacturing operations and effects substantial economies in production, characterized by the provision of a novel tuck or shank piece and a method of assembling the same in a shoe, especially of the open heel or sling type construction involving the provision of a tuck or shank piece and assembly thereof, having a feathered peripheral edge adjacent to and along the back of the heel, whereby in assembling the same with the outsole, the heel back may be consolidated with the outsole and in the assembly, the edge of the tuck or shank piece is made to vanish or blend into the edge of the outsole, to conform readily thereto in the assembly operation, and where embodied in an open heel or sling type shoe, be united at its peripheral edge as part of the sewing of the upper to the outsole; and still more particularly, the provision of a tuck including a shouldered

2

or slotted edge which serves as a guide for joining the contiguous edge of the upper adjacent the open heeled portion, leading to more accurate sewing operations and uniformity of appearance and fit of the resultant shoe.

My invention more particularly has for its object the provision of a novel tuck or shank piece and a shoe embodying the same, leading to the production of a more aesthetic appearance, especially in the production of a flexible, sling type or open heel woman's shoe.

To attain these objects and such further objects as may appear herein or be hereinafter pointed out, I make reference to the accompanying drawing forming a part hereof, in which—

Figure 1 is a perspective view of a tuck or shank piece in accordance with my invention, looking from the lower face thereof;

Figure 2 is a perspective view of the same, with the shank reinforcement outlined thereon;

Figure 3 is a perspective view of the sole assembly and tuck or shank piece embodying my invention;

Figure 4 is a section taken on the line 4—4 of Figure 3;

Figure 5 is a fragmentary perspective view of the sole assembly at the initial stage of attachment of the upper;

Figure 6 is a perspective view of the assembled shoe before applying the liner;

Figure 7 is a section on the line 7—7 of Figure 6, with the liner applied in position.

Summarizing my invention, it involves the provision of a novel tuck or shank piece and method of making flexible women's shoes, particularly the open heel or sling type shoe, wherein I provide a heel back to the tuck or shank

piece skived or beveled to a feather edge so that it, and particularly the shank reinforcement, may be integrated into the outsole, to eliminate the clumsy and awkward appearance at the back of the heel of the outsole, especially where visible

through the open heel portion of the shoe, and where assembled with a flexible sole, conform the assembly to secure a high degree of support, and in the assembly of the shoe, providing a more secure integration of the tuck or shank piece and by forming slotted or shouldered sides, acting as a guide in performing the stitching operation of the upper and securing uniformity of the shoe assembly.

Making reference to the drawing, I show a tuck or shank piece 10 made of material such

as stiffened fibre board, vulcanized board, integrated with impregnating agents to provide stiffness and toughness. The shank 11 thereof extends substantially unmodified toward the sole end 12 and is skived in the usual manner at 13. The heel end 14 is peripherally skived or beveled at 15, to provide a feather edge 16 along the sides and back of the heel. I prefer that the sides 17 and 18 of the shank portion merge into the thickened portion of the heel, with the beveled edge 15 forming shoulders 19 and 20, preferably sharply undercut at the corners 21 and 22, to provide an acute angle that is which may be 90° or less than 90°. With this construction provided, there is stapled or otherwise affixed the shank stiffener 23 which extends from the edge 13 to adjacent the heel portion 14, as will be recognized by those skilled in the art, the procedure of attachment bowing the assembly of shank stiffener and tuck or shank piece into approximately the desired arch supporting contour.

The tuck assembly illustrated in Figure 2 is thereupon used for attachment to the sole assembly shown in Figure 3 wherein an outsole 24 has superimposed thereon the insole 25. The outsole may be a composition soling material, such as rubber, and the insole may be a composition cork. Other materials will readily suggest themselves to those skilled in the art. The partial insole 25 is adhesively attached to the outsole, to leave the ledge 26 over the outsole 24.

Aligned with the insole, the tuck or shank piece is positioned to overlay the edge 13 over the insole and to conform the heel edge 16 to the heel edge of the outsole. In this position, the rows of stitches 28 and 29 are applied to unite the tuck or shank piece 10 to the outsole 24. The shaping pressure during sewing conforms the edge 16 to the heel edge 27. The cutout or shoulders 19 and 20 provide a ledge 30 continuous with the ledge 26 of the vamp portion of the shoe. Staples 31 may be used further to intimately unite the tuck or shank piece with the sole adjacent the heel portion 14 of the tuck or shank piece, the stapling operation being accompanied by an application of an adhesive in the interface between the tuck or shank piece 10 and the sole 24, to integrate the edges to the point where the feather edge is barely discernible.

With a sole assembly provided as shown in Figure 3, where an open toe sling type shoe is to be made, a patch 32 whose facing conforms to the upper is attached at the toe by the row of stitches 33 and the patch adhesively united to the insole 25. Thereupon the upper may be stitched to the sole assembly. For this purpose the upper 34 is attached to provide an outturned upper by stitching. For this purpose the sling edges 35, 36 are aligned with the shoulders 19 and 20 to abut the same, with the rows of stitches 37 and 38 for forming the outturned stitching operation extending to overlap the shoulders 19 and 20, anchoring the edge 16 adjacent the shoulders 19 and 20 to the outsole as well as anchoring the out-turned edges 39 and 40 of the upper to the ledge portions of the sole, previously described.

With this step accomplished, the edge 27 of the sole may be trimmed, buffed or otherwise treated with the tuck or shank piece attached thereto, without any special care, and the sole and upper assembly may then be attached to the heel 41 by the nails 42 in the usual manner.

Thereupon the liner 43 is overlayed, interposing preferably a heel cushion of foam rubber, felt or the like. The liner is formed with a shank portion 44, outlining shoulder portions 45 and 46, adjacent the heel portion 47. The heel portion is cut to conform to the heel assembly 27 and is accurately laid in the congruent position by abutting the shoulders 45 and 46 adjacent the edges 35 and 36, respectively, of the upper. The conforming relationship of the shoulders 19 and 20 of the tuck or shank piece to the upper permits the liner to be cemented or otherwise attached in position in conforming relationship, covering unsightly gaps and providing a neat and highly pleasing appearance by reason of the flush relationship of the shoulders 19 and 20 and the edges 35 and 36 contiguous to the sole.

By reason of the provision of the tuck or shank piece as described, and the method of assembly as described, a highly aesthetic shoe assembly, particularly of the sling type or open heel type, is provided, and substantial economies are effected in that the cost and expense of binding the tuck or shank piece to conform to the finish of the heel or upper are avoided. The flexibility of the tuck or shank piece adjacent the edge 15 permits a shaping of the assembly of stiffener 23 with the tuck or shank piece 10 and sole 24, to the concave contour of the heel with great facility, to add strength at the shank of the shoe without sacrificing the desirable yieldable characteristics of the material chosen for making the sole.

Having thus described my invention and illustrated its use, what I claim as new and desire to secure by Letters Patent is:

A shank piece for sling type shoes having an outturned upper comprising a heel end portion and a shank portion, the heel end portion adjacent the back being peripherally skived to substantially a feather edge along the sides and back thereof, the shank portion being inwardly stepped throughout the thickness of the shank piece from the peripheral edges of the heel portion at each side to an abrupt butt edge outlining shouldered ledges adjacent each side of the heel portion, said stepped ledges having the shouldered ledges each forming an acute angle with the side of the shank, the sides of the shank forming butt edges for the full thickness thereof, the ledges being extended to take stitches to each side of the shank coterminously with the outturned upper and the butt edges of the sides of the shank each forming shoulders for the outturned upper to be pressed against the same.

LOUIS BECKERMAN.
